UNITED STATES PATENT OFFICE

ROY T. GILES, OF PITTSBURGH, PENNSYLVANIA

CONCRETE ROAD LENGTHWISE FINISHING MACHINE

Application filed October 28, 1927. Serial No. 229,434.

The present invention relates to road finishing machines and has for one of its objects to provide a machine that will operate upon the road in a lengthwise direction to distribute road making material thereover and will at the same time finish the surface thereof, thereby eliminating many of the bumps and rough places in the road not overcome by machines operating in a different manner.

A further object is to so construct the traction mechanism of the machine that the side frames of the concrete road may be utilized as tracks for the finishing machine in which all oscillating side thrust is eliminated and by means of which a crowned surface of the road may be gradually changed to a flat surface.

A further object is to provide a machine for use in road building which will simultaneously shape and finish the road, and which will spread and distribute the material of which the road is being built.

A further object is to provide for adjustment of the finishing tools so that they may be raised off the surface of the road when the machine is moving backward over the work or for any other purpose.

A further object is to provide a machine which will finish the road free from bumps and rough places and will push forward the surplus material of which the road is constructed while at the same time the surface of the road is being finished.

A further object is to provide in a machine of the above character finishing means for the surface of the road which will push forward longitudinally of the road surplus material to fill in.

Other objects and advantages will appear from the following specification and will be set forth in the subjoined claims and I do not wish to be limited in the scope of my invention except as I shall be limited by the said claims.

Referring to the drawings which constitute a part of this specification:—

Figure 1 is a plan view of a machine constructed in accordance with my invention and showing the same as mounted on

the side rails of the roadway which are utilized in this manner as tracks.

Figure 2 is a front elevation of the machine.

Figure 3 is a side elevation thereof. 55

Figure 4 is a section on the line 4—4 of Figure 1 showing the relation of the parts.

Figure 5 is a fragmentary detail view showing the clutch operating mechanism, the same being in section on line 5—5 of 60 Figure 1.

Figure 6 is a fragmentary detail view showing tools for adjusting the drum carrying frame, the said view being taken on line 6—6 of Figure 4 looking in the direction of the arrows. 65

Figure 7 is a detail perspective of a portion of the clutch operating lever mechanism.

Figure 8 is a top plan view with parts removed and illustrating the frames of my machine, and the manner of hingedly securing the supplemental frame with the main or stationary frame. 70

Referring to the drawings in detail by reference numerals, the same numerals designating the same parts in all figures of the drawings, 10 designates a main frame which may be considered as stationary relative to the supplemental frame 11 which is hingedly mounted as at 12 upon a drive shaft 13 journaled in the frame 10. The frame 10 is provided with transverse axles 14 upon which are rotatably mounted wheels 15, while similar wheels 15 are similarly mounted on the ends of the drive shaft 13. The wheels are provided with flanges 15a on one side thereof. The axles 14 are journaled in the frame 10 for rotation relative thereto and the wheels of the drive shaft are provided on the flanged sides thereof with projecting clutch members 16, adapted to co-operate with clutches 17 slidably and non-rotatably mounted upon the drive shaft 13, the clutches being prevented from rotary movement by means of lugs 18 projecting into suitable grooves extending longitudinally of the shaft. The clutches 17 are movable longitudinally of the shaft by means of a yoked lever mem- 90

95
100
105

bers 19 pivoted as at 20 to suitable supports 21 extending from the frame 10, the upper ends of the levers 19 being curved as at 19a to receive therebetween the operating lever 5 22 pivoted to the lever 19 as at 23 and having lugs 24 at their lower ends abutting against the inner side of the lever 19 to cause rocking movement of the said lever members when the operating lever is moved 10 in one direction while movement in the opposite direction will not effect the position of the lever members 19.

By this arrangement, the clutches on the opposite sides of the machine which it will 15 be noted are connected only with rear axles, may be thrown out of engagement with the clutches of the traction wheels 15 selectively, thereby permitting the righting of the machine should one side move ahead of the 20 other. The rear wheels 15, are in driving connection with the front wheels through sprockets 25 formed thereon and sprocket chains 26 co-operating therewith.

Journalized to the supplemental frame 11 25 are vertical shafts 27, which carry at their lower ends surfacing and finishing drums 28, the supplemental frame 11 comprises upper and lower members 11a and 11b upon both of which members are secured the journals 29 and 30 for the shafts 27. The frame members 11a and 11b extend forwardly of the machine from each side thereof, said members converging toward the center of the machine and forming a support for the 30 shafts 27, so that the drums 28 will lie in staggered relation to each other from the apex as at 11d, each drum being disposed whereby the path of adjacent disks overlap a suitable distance, so that no portion of 40 the road will escape being operated upon thereby. The shaft 13 is in driven connection with a motor 31 which is mounted upon the machine, through sprocket wheels 32 and 33 respectively mounted upon the shaft 13 45 and upon the drive shaft 34, of the motor, the sprockets 32 and 33 being connected by means of sprocket chains 35. The upper ends of the shaft 27 are provided with sprocket wheels 36 secured thereto and are 50 in driven connection with the shaft 13 through chain belts 37 and 38 trained about the sprockets 36 and a driving sprocket 39 mounted upon a stub shaft 40 which is provided with beveled gears 41 articulating with 55 beveled gears 42 on the shaft 13. The belt 37 is maintained in contact with the sprocket wheels 36 on the ends of the shafts 27 by means of idlers 43 placed between the said sprocket wheels and rotatably mounted on 60 the upper member 11a of the supplemental frame. The belts 37 and 38 are caused to rotate in opposite directions, the forward part of the belts moving outwardly toward the sides of the machine for rotating each 65 set of drums operated thereby accordingly

in opposite directions. In other words one set is rotated in a clockwise direction, while the other set will be rotated in a counter-clockwise direction. On the ends of two of the shafts 27 are sprockets 44 and 45. 70 These sprockets as shown are mounted on the end or outermost shafts and are rotatable relative to said shafts and are provided with crank arms 46 and 47 for rotating the same. At intermediate points of the frame are provided screw shafts 48 and 49 to which frame members 11a and 11b are secured by means of collars 11c against longitudinal movement relative thereto, the shafts 48 and 49 being journaled in said 80 frame members for rotation relative thereto and having threaded connection with collars 50 secured to a cross member 10a to the stationary frame 10. The shafts 48 and 49 have secured thereto at their upper ends sprocket wheels 51 and 52 about which together with the sprockets 44 and 45 is trained a belt 53. By this construction by the rotation of the crank arms 46 and 47, it will appear, the supplemental frame 11 90 may be raised upwardly lifting the drums 28 off the surface of the road when such operation is desired for any purpose as for moving the machine rearwardly over a surface which has been worked upon. 95

It is believed that from the foregoing description, the operation will be apparent which is however, briefly as follows: When it is desired to use the machine in the making of a road, the machine is placed thereupon in the position such as shown in Figure 1 with the wheels 15 resting on the marginal iron forms 54 laid along the sides and forming the edge of the road, two wheels of the machine, one on each side are connected with the drive shaft 34 of the motor through the sprockets 32 and 33, sprocket chain 35 and drive shaft 13 and by means of which the machine is propelled along the roadway, the drums 28 being rotated through the shafts 40, the sprockets 39 and the sprockets 44 and 45 on the end shafts 27 and when it is desired to raise the drums off the ground, the crank arms 46 and 47 are rotated whereupon the threaded shafts 48 and 49 will raise the forward end of the supplemental frame 11 lifting the drums 28 off the ground. The frame 11 being hingedly connected to the shaft 13 as at 12, it will be readily understood that the front drum 28 will be raised first and that the distance of each drum rearwardly of the front drum from the road bed will be progressively diminished. It is possible therefore by means of this mechanism to gradually change the surface of a road from a flat to a crown finish or vice versa. 115

In making the road, the material of which the road is to be constructed is dumped out on the subgrade in piles and the machine is 120

5 moved along the side rails as stated above, and as each pile is reached it is spread and distributed evenly over the surface of the subgrade, the surplus material being pushed forward and the drums 28 rotating finish the surface as it progresses. Owing to the arrangement of the drums, material will not be permitted to pass to the rear of the machine or be left in unfinished condition. Should 10 however, the distribution and finishing be incompletely by the passing of the machine, the drums may be raised off the ground in the above manner and the direction of the machine reversed and backed to the rear of the imperfect portions of the road. The drums may be again brought into contact with the road and the machine moved forward.

15 A device of this character moving longitudinally of the roadway will produce a completely finished road of concrete or other road making material in a smoother and more uniform manner than the ordinary process now used by which the smoothing of the surface is accomplished by a transverse moving machine or the like, and my device will not only evenly distribute the material but will finish as well as properly grade the surface of the concrete or other 20 road making material employed, in accordance with the user's desires.

25 Further the provision of wheels on the side of the machine by which the said machine is guided by the side or marginal relations of the road will insure uniformity of 30 operation, relative to the roadway.

35 Having described my invention, what I claim is:—

1. A machine of the class described, comprising a frame, having wheels thereon, motive means on said frame connected with a certain of said wheels, a supplemental frame hingedly connected to the first named frame, surfacing and finishing drums rotatably carried by said supplemental frame, means for 40 rotating said drums and means for angularly moving said supplemental frame relative to said first named frame.

45 2. In a machine of the character described comprising a frame, flanged front and rear wheels supporting said frame and rotatably mounted relative thereto, a shaft extending through said frame upon which the rear wheels are mounted, clutch members on said shaft slidably and non-rotatably connected therewith, a clutch member on said rear wheels and means for selectively engaging said clutches with the clutch members on said wheels a supplemental frame movably secured to the first mentioned frame, means 50 rotatably mounted on said supplemental frame for surfacing and finishing longitudinally a road surface and means for receiving the wheels for guiding the machine 55 longitudinally of the road.

3. In a machine of the character described, comprising a frame having a transverse shaft at the rear end thereof, wheels mounted on and rotatable relative to said shaft, clutch members on said wheels and clutches slidably and non-rotatably mounted on said shaft, levers connected with clutches, said levers having pivotal connection with said frame and means for selectively rocking said levers on their pivotal connection for 60 engaging said clutches with said clutch members, means for driving said wheels, a supplemental frame hingedly connected to the rear portion of the first named frame, finishing and surfacing drums rotatably mounted on said supplemental frame, means for rotating said drums, screw shafts rotatably connected with the supplemental frame and having threaded connection with the first named frame and means for rotating 65 said screw shafts.

4. A road machine for gradually changing a crowned surface with no oscillating side thrust to a flat surface, comprising a plurality of juxtaposed drums, a supporting frame therefor, said drums being arranged in rearwardly and outwardly converging relation to each other from the center line of the machine, and each drum overlapping the patch of the next drum 70 thereto.

5. A troweling machine, comprising a plurality of troweling disks, a shaft supporting each disk, power means for driving said shafts, an auxiliary frame for supporting 75 said shafts and the disks carried thereby, a main frame for supporting said power means, said main frame being provided with traction wheels, and means for connecting the power means with the traction wheels, whereby the entire machine will be propelled 80 as the disks function.

6. A troweling machine, including a main frame, traction wheels for supporting said frame, a prime mover carried by said main frame, means for transmitting power from said prime mover to certain of said traction wheels for propelling the main frame and associated parts, an auxiliary frame mounted on the main frame, a plurality of rotatable troweling disks carried said auxiliary frame, and means for connecting said prime mover to said disks for rotating the same as the main frame is held over a surface.

7. A troweling machine, comprising a 115 plurality of groups of troweling disks, the disks of the respective groups operating in opposite directions, a shaft for supporting each disk, power driven means for rotating all of the disks at the same speed, a vertically adjustable auxiliary frame carrying said shafts, and a main frame carrying the auxiliary frame.

8. A troweling machine, including a plurality of rotating troweling members, a main 120

frame provided with traction wheels, an auxiliary frame vertically adjustable on the main frame, and means on the auxiliary frame for supporting and actuating said troweling members.

In testimony whereof I affix my signature.

ROY T. GILES.
